PEDESTAL FOR TABLES AND THE LIKE

Filed June 27, 1932

UNITED STATES PATENT OFFICE

JOHN W. BEIGER, OF LUDINGTON, MICHIGAN

PEDESTAL FOR TABLES AND THE LIKE

Application filed June 27, 1932. Serial No. 619,379.

The main object of the invention is to provide means whereby the legs of pedestal tables and the like may be readily adapted to rest squarely on the floor regardless of variations in the floor and/or the table.

Objects relating to details and economies of the invention will appear from the description to follow. The invention is defined and pointed out in the claims.

10 A structure which is a preferred embodiment of my invention is illustrated in the accompanying drawing, in which:

Fig. 1 is a perspective view of a pedestal table of the type used for banquet purposes.

15 Fig. 2 is a greatly enlarged side elevational view of the end portion of the pedestal leg having a preferred embodiment of my invention incorporated therein.

Fig. 3 is a cross sectional view taken on line 20 3—3 of Fig. 2, and

Fig. 4 is a perspective view of a four-legged pedestal suitable for a single pedestal table.

Referring to the drawing, 1 represents a pedestal table to be used for banquet purposes and the like, having a top 2 which is supported by vertical studs 3 having pedestal legs 4 attached to the bottom thereof.

As usual, the pedestal legs 4 are four in number and one of these legs has its bottom surface 5 spaced away from and angularly related to the horizontal supporting surface or floor for the table.

The bottom surface 5 is provided with a longitudinal groove 6 therein for the accommodation of a tongue 7 adapted to slidably register therewith. The tongue 7 extends upwardly from the upper surface of a wedge-shaped foot 8, the bottom surface 9 of which is substantially horizontal. The upper surface 10 of the wedge-shaped foot 8 is adapted to register with the bottom surface 5 of the leg.

A longitudinal recess 11 is provided in the bottom of the foot 8 and a longitudinal slot 12 extends from the bottom thereof to the top of the tongue 7, as clearly illustrated by Figs. 2 and 3. The width of the slot 12 is somewhat smaller than the width of the recess 11 so that a shoulder 13 is provided in

the bottom of the recess 11 around the periphery of the slot 12.

A wood screw 14 is secured to the bottom of the leg 4 in the groove 6 which extends through the slot 12 of the foot 8. The head 15 of the screw 14 supports a washer 16 which projects over the shoulder 13 and retains the foot 8 in slidably engagement with the bottom surface 5 of the foot 4 in line with the coacting slot 6 and tongue 7 of the foot and leg, respectively.

In Fig. 4, is shown a four-legged pedestal with a vertical stud 3 and four pedestal legs 4. A pedestal of this type is suitable for a single pedestal table or may be used on a table such as is shown in Fig. 1. On the bottom of one of the legs is the foot 8 constructed as above described and adapted to be used to level the table.

It will be apparent that with this simple device on one of the pedestal legs the table may be adjusted so that it will not rock by merely tapping slightly the inclined block or foot 8. If the foot 8 happens to be in too far so that the table is resting thereon, it is merely necessary to shove the table slightly and the foot 8 will adjust itself automatically so that the table will not tilt. The device is simple and economical in addition to being a great convenience in adapting the legs of tables and the like to rest squarely on the floor regardless of variations in the floor and/or the table.

While I have shown the groove in the bottom of the leg 4 and the registering tongue on the foot 8, it will be obvious that this may be reversed with the tongue on the bottom of the leg and the groove at the top of the foot. Various other changes may be made in the details of my construction without departing from the spirit of invention, and it is to be understood that the invention is only limited by the prior art and the scope of the following claims.

Having thus described my invention, what I claim as new and desire to secure by Letters Patent is:

1. The combination with a pedestal leg having a bottom surface angularly related to the horizontal and a longitudinal groove

therein, of a wedge-shaped foot having a tongue slidably registering with said groove, said foot having a longitudinal recess in the bottom thereof and a smaller slot extending from the bottom thereof to the top of said foot, a pin-like member secured to the bottom of said pedestal and extending through said slot and having a head projecting over the bottom of said recess whereby said foot is slidably attached to said leg and is capable of adjustment relative thereto.

2. In a banquet table and the like having four pedestal legs, the combination with one of said legs having a bottom surface angularly related to the horizontal and a longitudinal groove therein, of a wedge-shaped foot having a tongue slidably registering with said groove, said foot having a longitudinal recess in the bottom thereof and a smaller slot extending from the bottom thereof to the top of said foot, a pin-like member secured to the bottom of said pedestal and extending through said slot and having a head projecting over the bottom of said recess whereby said foot is slidably attached to said leg and is capable of adjustment relative thereto to cause the four legs to rest squarely on a supporting floor.

3. The combination with a pedestal leg having a bottom angularly related to the horizontal and a longitudinal groove therein, of a wedge-shaped foot for said leg having a tongue extending into said groove and a slot therein, and a screw secured to said leg and

35

extending through said slot whereby said foot is slidable in line with said groove relative to said leg.

4. The combination with a pedestal leg having a bottom angularly related to the horizontal and a longitudinal groove therein, of a wedge-shaped foot slidably mounted on the bottom of said foot and having a longitudinal tongue extending into said groove, the bottom of said foot being substantially horizontal.

5. The combination with a pedestal leg having a groove in the bottom thereof, of a wedge-shaped foot for said leg having a tongue extending into said groove, and means securing said foot to said leg whereby said foot may be adjusted relative to the leg in any desired position.

6. The combination with a pedestal having a plurality of legs with one of said legs having a bottom surface angularly related to the horizontal and a longitudinal groove therein, of a wedge-shaped foot having a tongue slidably registering with said groove, said foot having a longitudinal recess in the bottom thereof and a smaller slot extending from the bottom thereof to the top of said foot, a pin-like member secured to the bottom of said pedestal and extending through said slot and having a head projecting over the bottom of said recess whereby said foot is slidably attached to said leg and is capable of adjustment relative thereto.

JOHN W. BEIGER.
